WINDING CONTROL MEANS FOR MAGNETIC RECORDING AND REPRODUCING APPARATUS

Semi Joseph Begun, Cleveland Heights, Ohio, assignor to Magnetone, Inc., Cleveland, Ohio, a corporation of Ohio

Application January 31, 1946, Serial No. 644,600

14 Claims. (Cl. 179—100.2)

1

This application is in part a continuation of application Serial No. 499,795, filed August 24, 1943.

This invention relates to magnetic recording and reproducing apparatus, and more particularly to such apparatus utilizing as a magnetic recording medium a thin flexible magnetic record member, such as a wire, filament or tape which may be stored on reels for carrying on magnetic recording and reproducing operations.

Among the objects of the invention are novel magnetic recording devices of the foregoing type embodying various features which make them foolproof and simple in operation and which eliminate difficulties heretofore encountered with such devices.

The foregoing and other objects of the invention will be best understood from the following description of exemplifications thereof, reference being had to the accompanying drawings wherein

Fig. 1 is a simplified diagrammatic view illustrating the general relationship of the mechanical, magnetic and electric elements of a magnetic recording and reproducing apparatus exemplifying the invention;

Fig. 1—A is a diagrammatic view similar to Fig. 1 of a modified form of drive control arrangement based on the principles of the invention;

Fig. 1—B is a diagrammatic view similar to Fig. 1—A of another drive control arrangement exemplifying the invention;

Figs. 1—C and 1—D are generally diagrammatic side and plan views of a modified form of drive control arrangement for a magnetic recorder of the type shown in Fig. 1;

Fig. 1—E is a perspective view of some of the elements of the control arrangement shown in Figs. 1—C and 1—D;

Fig. 2 is a diagrammatic view and circuit diagram of another recorder of the invention; and

Fig. 3 shows a detailed view of part of the control arrangement of the recorder of Fig. 2, being a section along line 3—3 of Fig. 2.

Fig. 1 illustrates in a simplified diagrammatic manner the general relationship of the mechanical, magnetic and electric elements of a magnetic recording and reproducing apparatus exemplifying the principles of the invention. A magnetic recording medium in the form of a thin flexible magnetic record member, such as a magnetic record wire, filament or wire-like tape 31, is arranged to be reeled on take-up reel 33 from supply reel 34, which are shown

2

driven by a drive mechanism, including a drive shaft 4—13 and a drive shaft 4—14, to which the two reels 33, 34, respectively, are coupled.

In the specific arrangement as seen in Fig. 1, magnetic recording and reproducing operations are carried on when the recording medium 31 is impelled in the forward direction indicated by arrow 31—A by driving and rotating reel 33 in counterclockwise direction looking from below Fig. 1. In order to play back the recorded program or to make a new record on the recording medium 31, it must be rewound on the supply reel 34 which is then driven and rotated in clockwise direction, as seen from below Fig. 1, the directions in which the two reels are driven being indicated by arrows applied to the schematically indicated brake drums 2—21 associated with the two reels 33, 34, respectively.

In moving from one reel toward the other, the recording medium 31 is guided through a magnetic record transducer head structure 36 which operates to magnetically record, play back as well as erase the signals recorded on the recording medium 31. In the particular arrangement shown, the transducer head is also utilized for level winding the recording medium on the reel on which it is reeled. The transducer head structure 36 is not part of the invention and may be of any type.

In order to simplify the description of the circuits by means of which the recording, play-back and erasing operations are performed, the elements of the transducer head structure 36 are also indicated in the circuit diagram of Fig. 1 by a dash-line rectangle 36—A, and is there shown provided with an erasing head 37 and a record transducing head 38. Each of the heads 37, 38 is shown provided with windings and a magnetic core structure which has pole pieces separated by a non-magnetic gap past which the recording medium 31 is moving in the direction of the arrow 31—A. The recording medium 31 is guided through the transducer head structure so that during the recording operation each element of the recording medium passes successively first past the gap region of the erasing head 37 and then past the gap region of the record transducing head 38.

The recording system shown in Fig. 1 is arranged to carry on magnetic recording and reproducing operations under the control of a multi-blade selector switch generally designated 40 which is shown provided with a plurality of contactor blades 40—1, 40—2, 40—3, 40—4, 40—5, 55 which are moved as a unit to one of a plurality

of different contact positions, the numerals 1 to 5 applied to some of the contact positions indicating the different contact positions of the selector switch 40. Contact blades 40-1 to 40-3 of the selector switch 40 establish the recording circuits when the contact blades are in position 1 and they establish the playback circuits when the contact blades are in position 2.

When the selector switch is in the recording position 1, its contact blade 40-3 connects a 10 source of high frequency oscillations or an oscillator 41 to a source of positive power supply indicated by a plus (+) sign, which is connected to the contact blade 40-3, the circuit as well as other analogous circuits described hereinafter being completed by the ground connections shown, to which is also connected the negative terminals of all D. C. supply sources.

The high frequency erasing current supplied by the oscillator 41 to the erasing head 37 is of 20 sufficiently large amplitude so that each longitudinal element of the thin moving magnetic recording medium 31, passing the gap region of the erasing head 37, is subjected to an alternating flux strong enough to erase any previous magnetic signal records of the moving medium and restore the magnetic elements thereof to a magnetically neutral condition. After being subjected to the magnetic erasing action by the erasing head 37, each element of the moving recording medium 31, upon reaching the gap region of the record transducing head 38, is subjected to a magnetic recording flux produced by the amplified signal currents which are to be recorded and a superimposed high frequency biasing flux component.

In Fig. 1, a conventionally shown microphone 42 serves as a source of the signals which are to be recorded and a reproducing device, such as a loudspeaker 45 serves to reproduce the signals. During a recording operation, the microphone is connected by way of contact blade 40-1 to the input side of an amplifier 43, the output of which is supplied by way of contact blade 40-2 of the selector switch to the windings of the recording head 38 which records the signals, the circuits being completed by the ground connections shown.

The high frequency bias component of the recording flux is provided by a high frequency current component derived from the oscillator 41 by a circuit, such as shown, which includes an adjustable coupling condenser 44 for supplying an adjustable component of the high frequency oscillations to the output circuit of the amplifier 43 where it is mixed with the amplified signal currents and supplied to the windings of the transducer head 38 which records the signals. The coupling condenser 44 and the other circuit elements of the system are designed to mix a suitable component of the high frequency oscillations derived from the oscillator 41 with the amplified signal current supplied by the microphone in such manner as to produce in the gap region of the recording head 38 the desired combination of the signal recording flux and the superimposed high frequency biasing flux component.

In general, when recording signals of the audible frequency range, good results are obtained by using a high frequency biasing flux of about 25 kilocycles per second and the same source of high frequency signals may be used for supplying a relatively large high frequency erasing current to the erasing head 37 as well as the

small high frequency biasing component to the recording head 38.

To play back the magnetically recorded signals while the recording medium is moving in the same direction as during the recording process, the selector switch 40 is actuated to the playback position 2. When the selector switch is in the playback position 2, its contact blade 40-3 disconnects the oscillator 41 from the source of power supply, thereby de-energizing the oscillator, and no high frequency erasing or biasing currents are supplied to the erasing head 37 and the transducer head 38. Furthermore, selector contact blades 40-1, 40-2 now connect the windings of the record transducer head 38, which operates now as a playback head, to the input side of the amplifier 43, the output of which is now supplied after amplification in an additional amplifier stage 43-A to the reproducing device 45 for reproducing the signals.

In the magnetic recording device shown in Fig. 1, the two reels 33, 34 with the recording medium stored thereon form part of a self-supporting detachable guide unit 2-10 designed for detachable interconnection with a motor or drive unit 4-10. The drive unit 4-10 is shown in the form of a casing in which are housed all the elements of the driving mechanism as well as the amplifier and the principal control elements of the device, and supplies the mechanical power required for reeling the magnetic recording medium from one reel to the other.

The drive mechanism of the drive unit 4-10 has a drive motor 4-20 which may be provided with a built-in speed reducing mechanism so as to drive a motor drive shaft 4-22 at a speed at which it may be directly coupled to the drive shaft 4-13 of the take-up reel 33 for driving it at the speed proper for carrying on recording or reproducing operations. The driving mechanism of the recording device shown is so designed as to assure that when one of the reels 33, 34 is driven for reeling thereon the recording medium, the other reel will at all times be subjected to a braking action sufficient to maintain the recording medium under tension, and that when the direction of the motion of the recording medium is reversed, the removal of the driving forces from one reel and the application to the other reel is controlled in a predetermined time sequence to assure that the two reels and the moving recording medium are first brought to a positive stop before the driving forces are applied to the other reel. The selective application of the driving forces to each reel is interlocked and subjected to the control of time action means so that whenever the application of the driving forces is reversed, the reel mechanism is first brought to a positive stop before the driving forces are applied to the other reel.

In the arrangement shown, the drive control mechanism includes coupling means, generally designated 4-30, for selectively coupling the motor drive shaft 4-22 either directly to reel drive shaft 4-13 or through a speed step-up mechanism to the other reel drive shaft 4-14 for driving the supply reel 34 in clockwise direction at an increased speed during the rewinding operation.

In the arrangement shown, the coupling means comprise slidably mounted coupling members 4-31, 4-32 which are operated by a coupling lever 4-35 from the position shown in which coupling member 4-31 establishes a direct coupling connection between the motor drive shaft 4-22 and the reel drive shaft 4-13 of the take-

up reel 33 for rotating it in forward direction—or to the opposite coupling position indicated by dash-dot lines 4—35—R—in which coupling member 4—31 breaks the coupling connection from the motor drive shaft 4—22 to the drive shaft 4—13 of the take-up reel, and instead couples the motor drive shaft 4—22 to gear 4—36 of a train of step-up gears including gear 4—31, while the other coupling member 4—32, which is now in reverse coupling condition, couples the gear 4—37 to the rewind drive shaft 4—14 for rotating the supply reel at a higher speed in clockwise direction.

The control lever 4—35 is shown pivotally mounted on a fixed pivot 4—41 and one end thereof is connected through a pivot pin 4—44 to a spring-loaded toggle arm 4—43, the other end of which is pivotally held on a fixed pivot 4—45. The toggle arm 4—43 is formed of two telescopically mounted sliding toggle arm sections, the ends of which are biased apart by a compression spring 4—46 so that when the coupling lever 4—35 is moved past a center position, its toggle arm 443 with its compression spring 4—46 will bring the coupling lever either to the forward coupling position shown or to the opposite rewind coupling position indicated by dash line 4—35—R.

The coupling mechanism of the type described may be controlled either mechanically or electrically. In order to provide for remote control, the coupling mechanism shown is electrically controlled. In the form shown, the electrical control comprises two relay or solenoid members 53—F, 53—R held in fixed position and having core or armature members which are pivotally interconnected to moving portions of the coupling lever so that when the forward solenoid 53—F is energized, the coupling lever 4—35 will be actuated from the dotted line position 4—35—R to the full line position shown, and that when the rewind solenoid 53—R is energized, the coupling lever will be actuated to the dash-line position 4—35—R.

The drive control mechanism shown is arranged to utilize only a single time action means for assuring that whenever the drive control mechanism is actuated from either one or the other drive position to a standby position or to the opposite drive position, the time action means are actuated to make it impossible to establish the opposite drive connection until after a predetermined time action sufficient to assure that the reels have been brought to a stop before the opposite drive connection could be established, if the drive control mechanism is actuated to the opposite drive control position.

Fig. 1 illustrates in a simplified diagrammatic manner one form of such drive control arrangement. It utilizes as a time action means a single time delay relay 61, which is arranged to open its contacts 62 instantaneously upon the de-energization of the relay and to reclose with a desired time delay when the relay is energized, or, in other words, to instantaneously open a control circuit and to close the control circuit with a required time delay. The desired time action of relay 61 is supplied by a circuit including a condenser 63 and a resistor 64 interconnected with a condenser charging circuit which is controlled in such manner that the time required for charging the condenser to a predetermined potential determines the time delay with which relay 61 operates.

In the arrangement shown, the charging current to the condenser 63 is controlled by an elec-

tron tube 65 having an anode as well as a cathode 67 and a control grid 68. The positive terminal of a supply source indicated by B+ is connected to the anode of tube 65, the cathode 67 being connected through the winding of relay 61 and resistor 70, the circuit being completed by a ground connection to which the negative terminal of the B+ supply source is also connected. A resistor 69 is used to connect the B+ source with the ungrounded end of resistor 70.

The circuit elements associated with tube 65 and relay 61 including the condenser 63 and resistor 64 are so designed that when the cathode is maintained at its normal temperature by suitable heating means, not shown, and the anode is energized as indicated, the condenser 63 will be charged by current flowing through the tube so as to apply to the control grid 68 a potential which causes the tube to pass sufficient current for energizing the relay 61 and cause it to keep its contacts 62 closed as long as no negative blocking potential is applied to the control grid 68 of tube 65.

The arrangement is such that when a negative blocking potential is applied to the control grid 68 of the tube, the current flow through the winding of relay 61 will be stopped or reduced and cause it to instantaneously open its contacts 62. The condenser 63 and the resistor 64 are so proportioned and interconnected with the other circuit elements associated with tube 65 that when the negative blocking potential is removed from control grid 68, the required time delay will elapse before the current flow is able to charge up the condenser 63 through the resistor 64 to the proper potential at which the control or bias applied to the control grid 68 enables the tube to send through the winding of relay 61 a current sufficient for actuating the relay to close its contacts 62.

In the arrangement shown, the blocking potential is applied to the control grid 68 of tube 65 by the operation of the selector switch 40 which is utilized to control the recording, playback as well as the rewinding operations. Selector contact blade 40—4 applies a negative blocking potential to the control grid 68 whenever it is moved to or past position 3 from either one of its other positions 1, 2 or 4, 5. As a result, the relay opens each time the selector switch 40 is moved either from positions 1 and 2 to position 3 or from positions 5 and 4 to position 3, or from either one of positions 1 and 2 to either one of positions 4 and 5, or vice versa.

As explained above, the reversal of the driving connection to the reels or, in general, to the impelling elements which impel the recording medium, is controlled by the operation of the selector switch 40 and particularly by its set of contact blades 40—3, 40—4, 40—5. The drive control circuits also include a normally closed forward limit switch 51—F which opens whenever the limit of the forward reeling motion is reached, a normally closed rewind limit switch 51—R which opens whenever the limit of the rewinding operation is reached, a latch switch 53 which is biased to an open position and is closed only if the detachable reel holder and drive unit 2—10 is latched in its coupled position to the drive unit 4—10, and two auxiliary relays, namely, the forward relay 55—F and a rewind relay 55—R.

The drive control circuit further includes a set of control contacts 56—F, 57—F which are operated from their normal, respectively closed

and open positions, to the operative positions shown when the coupling lever, or, in general, the coupling means, are actuated to establish a forward drive coupling connection and a set of similar switches 56-F, 57-R which are operated from the normally biased positions shown to the operative positions when the coupling means are actuated to establish rewind driving connections. In the arrangement shown, the switches 56-F, 56-R control the selective energization and de-energization of the two coupling solenoids 55-F and 53-R so as to de-energize a solenoid after it has been energized and has performed a drive reversal operation. The two other switches 57-F, 57-R control the energization of the drive motor 4-20 and operate to permit energization of the motor only when the drive reversing operation has reached a predetermined stage at which the energization and driving action of the motor are desirable.

In particular, the two sets of switches are shown controlled by a finger plate 4-49 suitably affixed to the control lever 4-35 so as to move therewith and is provided with two sets of fingers 4-47, 4-48 for operating the two sets of coupling control switches 56-F, 57-F, 56-R, 57-R. The switches 56-F, 57-F, 56-R, 57-R as well as the similar other switches shown are of the micro-switch type which operate with a snap action when actuated by a push pin or similar actuating element. In the arrangement shown, the several switches which are operated by the control lever 4-35, or, in general, the coupling control means, are designed to operate in the following manner:

It is assumed that the drive mechanism is in the condition shown in which the coupling mechanism establishes the driving connection from the motor 4-20 to forward drive reel shaft 4-13. In the arrangement shown, the reversal of the drive connection is controlled by the selective closure of the contacts of either the forward drive relay 55-F or rewind drive relay 55-R, which also serve to control the energization of the motor. The two auxiliary relays 55-F, 55-R perform merely the auxiliary function of making it possible to separate the power line circuits which supply operating power for the motor 4-20 and the coupling solenoids 53-F, 53-R from the operating circuits which are used for remotely controlling the operation of the drive mechanism and the recording and reproducing operations from low power relay supply sources which are indicated in the diagram by the plus (+) sign connected to switch blade 40-5 and ground connection.

With the mechanism in the condition shown, when the contacts of rewind relay 55-R are closed, current will be sent from one terminal of a source of power supply indicated by a double plus (++) sign through the closed coupling interlocked contacts 56-R, and through the rewind solenoid 53-R, the energized circuit of which is completed only if the time delay relay 61 closes its contacts which connect the circuit to the other terminal of the power supply indicated by a double minus (--) sign, the double plus (++) and double minus (--) signs being used for the sake of simplicity to indicate a conventional source of power which may be either an alternating current source or a direct current source for supplying power to the motor and to the operating elements, such as the solenoids 53-F, 53-R of the coupling mechanism.

Upon energization, the rewind solenoid 53-R

will start moving the coupling lever 4-35 from the coupling position shown toward the dash-dot line position 4-35-R. The two coupling interlock switches 56-R, 57-R which are operated by the control lever as it moves towards the rewind coupling position are arranged to be actuated in a predetermined sequence in order to assure that the motor energizing switch 57-R operates to energize the motor before the coupling member 4-32 has established coupling engagement with the coupling teeth of the coupling member 4-32-R through which it is coupled to the rewind drive shaft 4-14, and that the coupling interlock switch 56-R shall operate to open and de-energize the rewind solenoid 53-R after the coupling teeth of coupling elements 4-32, 4-32-R are sufficiently engaged and the coupling lever is past the over-center position. The other set of coupling interlock switches 56-F, 57-F are arranged to operate in an analogous manner when the forward solenoid 53-F is energized to operate the coupling mechanism to reverse the drive connection from rewind to forward drive.

With the foregoing arrangement, the drive mechanism will drive the recording medium in forward direction whenever the contacts of forward relay 55-F are closed, provided the coupling mechanism is in the forward coupling position. Similarly, the driving mechanism will drive the recording medium in the rewind direction whenever the contacts of rewind relay 55-R are closed, provided the coupling mechanism is in the rewind coupling position indicated by the dash-dot line 4-35-R.

Since the circuits controlled by the forward drive relay 55-F and rewind relay 55-R serve also to control the operation of the coupling reversing solenoids 53-F, 53-R, the selective energization of either of the contacts of one or the other of the drive control relays 55-F, 55-R will also bring about a reversal of the coupling connections if one or the other of the relay contacts is actuated to the closed position for driving the recording medium in one direction while the coupling mechanism is in a position in which it establishes a driving connection in the other direction.

Thus, if the drive mechanism is in the condition shown in Fig. 1 in which the drive shaft of motor 4-20 is coupled to the drive shaft 4-13 of the take-up reel for driving it in forward direction, and the contacts of the rewind relay 55-R are actuated to the closed position, it will complete a circuit leading by way of the closed coupling interlock contacts 56-R to the solenoid 53-R bringing about its energization, provided the contacts of the time delay relay 61 are closed; whereupon, the rewind solenoid 53-R will be operated to reverse the coupling connection from the position shown to the position corresponding to the rewind drive position indicated by the dash-dot line 4-35-R. When so actuated to the rewind position, the movement of the coupling mechanism automatically operates the interlock contacts 56-R, 57-R to successively energize the motor and de-energize the rewind solenoid 53-R as it reaches the rewind coupling position of dash-dot line 4-35-R.

In other words, the circuit leading to the two selectively operating contacts of the forward drive relay 55-F and the rewind drive relay 55-R may be directly utilized for controlling the operation of the drive mechanism to start and stop the driving action in one or the other direction or to

at any time reverse the driving motion, in which case, however, the operation of the time action means 61 delays the reversal of the driving connections until the mechanism has been brought to a stop. In the arrangement shown, the selective actuation of the drive relays 55-F, 55-R is controlled by the operation of the selector switch blades 40-4, 40-5 by bringing them from a standby position 3 to any one of the forward drive positions 1, 2 or to any one of the rewind positions 4, 5.

Thus, when the selector switch blade 40-5 is in any one of the forward drive positions 1, 2, as shown in Fig. 1, the two selector switch blades establish the following energizing circuit for the forward drive relay 55-F: From the selector contact blade 40-5 which is connected to one terminal of the relay supply source, through the winding of the forward drive relay 55-F, through the contacts of the forward limit switch 51-F to the normally closed contacts of the latch switch 53, and then through a common circuit portion leading to the contacts of contact positions 2, 4, 5 of the selector contact blade 40-4 to which there is also connected the drive operating switch 58 which is shown used to set the drive mechanism in motion for forward drive during a recording operation.

Thus, with the arrangement shown, the forward drive relay 55-F will be energized and operated whenever the contact blades 40-5, 40-4 are in the playback position 2 and also when they are in the recording position, in which case, however, the operation of the forward relay 55-F to start and stop the drive will be controlled by the push-button drive switch 58 which may be combined with a microphone so that the person recording may stop the recording operation and start the recording operation as he transmits with the microphone the desired message.

In an analogous manner, the rewind drive relay 55-R will be energized to operate its contacts and cause the recording medium to be rewound whenever the selector contact blades 40-4, 40-5 are in either positions 4 to 5. It will be noted that when the selector switch 40 with its drive control blades is actuated from either one of positions 1, 2 to either one of positions 4, 5, or vice versa, contact blade 40-4, on reaching or moving past the standby position 3, applies a blocking potential to the control circuit of time delay relay 61, thereby instantaneously causing it to open its contacts and de-energize the operating circuits of both coupling solenoids. Because of the time delay action in reclosing its contacts, the time delay relay 61 will keep the energizing circuits of the coupling solenoids 53-F, 53-R de-energized for the time required in order to bring the motor to a stop, in all cases when the selector switch 40 has been actuated from either one of the forward drive positions 1, 2 to either one of the rewind positions 4, 5, or vice versa.

It will be noted that whenever the selector switch blade 40-4 is in the standby position 3 or is returned to the standby position 3 from any of the drive positions, it will apply a blocking potential to the control circuit of the time delay relay 61 and instantaneously release its contacts to its normally open position in which it de-energizes the coupling reversing solenoids 53-F, 53-R.

The arrangement of the type described above makes it possible to discontinue at any time a recording or playback operation and start a re-

winding operation by moving the selector switch from either one of positions 1, 2 to either one of positions 4, 5, in which case the rewind operation will be started after the time delay provided by the time action of the time action relay 61. In a similar way, a rewind operation may be discontinued at any time and changed over to a recording or playback operation by moving the selector switch from any one of positions 4, 5 to any one of positions 1, 2, in which case the forward drive will be started after the time delay provided by the time action relay 61 to assure that the recording medium and the reels have been first brought to a stop before starting to move in reverse direction.

It will be noted that with the drive mechanism in the forward drive position shown, actuation of the selector switch from the standby position to any one of the forward drive positions 1, 2 will start the forward drive at once, without any time delay. Similarly, in the event the drive coupling connection has been previously reversed to establish the rewind connections indicated by dash-dot line 4-35-R, a rewind operation will be started instantaneously without any time delay by merely moving the selector switch from the standby position to any one of the rewind positions 4, 5.

The contact blades of the selector switch 40, in addition to performing in their different operating positions the various functions described above, are also utilized to perform additional operations interlinked with their operations thus far described. Thus, in the recording position 1 of the selector switch, selector switch blade 40-3 applies the full positive potential to the oscillator 41 for energizing it to supply the erasing as well as the biasing currents, while at the same time the source of positive supply which is connected to this selector switch blade is also connected through a voltage reducing resistance 73 to the screen grid of a tube of the additional amplifier stage 43-A, thereby reducing the anode current drain of this amplifier stage without in any way impairing the operation of the principal amplifier 43 which serves to amplify the signal currents which are supplied to the recording head 38.

However, in the playback position 2 as well as in the rewind position 4, the selector switch blade 40-3 applies the full positive potential to the screen grid of the additional amplifier stage 43-A so that the auxiliary amplifier 43-A operates with full efficiency to amplify the recorded signals reproduced by the transducer head 38 now operating as a playback head to secure efficient reproduction of the record by reproducing device 45. In the arrangement shown, the record playback process is also carried on during the rewinding operation for playing back the recorded signal sequence in reverse direction. This is desirable in many applications, because with a little experience, a user of such recording device will be able to distinguish and recognize from the scrambled sequence of the recorded signals played back during a rewinding operation one or another part of the previously recorded message which he desires to playback. In such case, he has merely to stop the rewinding operation and actuate the selector switch 40 to play back the desired sequence. In order to provide for the playback operation during the rewinding process, selector switch blades 40-1, 40-2 complete in contact position 4 the same playback circuits which they established in position 2, as described above.

Furthermore, selector switch blade 40-1 ap-

11

plies a ground connection to the input side of the amplifier 43 when the selector switch is in the standby position or in the special rewinding position 5 which may be utilized for subjecting the recording medium to a special erasing operation, for instance, to erasure by a direct current supplied to the recording head, in which case the positive terminal of a suitable direct current source is connected to the contact element of contact position 5 of selector switch blade 40-2.

Instead of using time action means using electric circuit elements for determining the time delay, such as described above in connection with the time delay relay 61, other forms of time action means may be used. Thus, for instance, a spring driven member, such as an arm of a spring-driven clock work, may be used as the timing element for interposing a required time delay each time a drive control action is performed for reversing the direction of the drive forces applied to the recording medium or a drive control action which might be followed by an action which results in the reversal of the driving forces applied to the recording medium, so as to prevent reversal of the driving forces applied to the recording medium before the recording medium is first brought to a stop.

Such modified time action means may be combined with a relay, such as relay 61 shown in Fig. 1, so that the time action means operates to reclose the relay contacts with the required time delay, the relay contacts and the timing mechanism being combined so that whenever the relay winding is energized the contacts open instantaneously and at the same time cause the time action means to be charged for performing the desired timing action. Such time action relay means operating with a spring-driven timing mechanism are well known in the art and need not here be described. A relay 61 combined with such time action means may be controlled in the same manner as described above so that each time the selector switch is operated from a forward drive or rewind drive position to the standby position, the relay 61 is energized to instantaneously open its contacts, the contacts being reclosed under the control of the time action means with the required time delay for restoring the conditions under which a reversal of the driving connection or, in general, a reversal of the application of the driving forces to the recording medium may be accomplished.

Instead of using a contact blade of a selector switch, such as selector blade 40-4, for actuating the time action means to block a reversal of the driving connection each time the selector switch is actuated to reverse the driving connections, the time action means may be arranged to be operated each time the selector switch is moved from one control position to another control position for interposing a timed preventive action which prevents a reversal of the driving connection or, in general, a reversal of the driving forces applied to the recording medium until the end of the timing interval necessary to assure the stopping of the recording medium.

In Fig. 1-A is shown one form of such modified drive control arrangement in which conventional time action means are instantaneously actuated to the blocking condition in which it prevents the drive mechanism from completing a drive reversing operation during a predetermined time delay, whenever the drive control means such as selector switch 40, shown in Fig. 1, is actuated from any one of its operating to another oper-

12

ating condition. The rotary shaft of the selector switch 40 which carries the various contact blades 40-1 to 40-5 has also secured thereto an actuating member shown in the form of a cam sector 81 provided with a plurality of cam projections 82 arranged so that whenever the contact blades of the selector switch are moved from one position to the other, one or another of the cam projections operates a suitably mounted switch 83.

10 As indicated in Fig. 1-A, the switch 83 serves to control the operation of time action means to instantaneously disable the drive reversing mechanism for the duration of a predetermined timing interval required to assure that upon performing a drive reversing operation, the recording medium is brought to a stop before driving forces are applied thereto in opposite direction.

As explained above the time action means may be a mechanically timed mechanism which is indicated in Fig. 1-A as a dash-pot relay 61-1 arranged to instantaneously open its contacts 61-2 upon energization of the relay and to reclose its contacts after a predetermined adjustably set timing period following the re-energization 25 of the relay.

The contacts 61-2 of the time action relay 61-1 may be connected in the control circuit leading from one terminal of an electric power source to the two coupling solenoids 53-F, 53-R 30 so that each time the time action relay 61-1 is energised, it instantaneously opens its contacts 61-2 thereby disabling the coupling reversing mechanism for the period of the required timing interval.

35 Alternatively, the cam projections 82 of the drive control selector means 40 may be utilized for operating a mechanical latch member to interlocking engage and lock a mechanical element of the coupling mechanism each time such drive 40 control selector is actuated from one operating position to the other, the time action means permitting the return of the latch member to the coupling releasing position only after the lapse of the required timing interval.

45 Instead of using a rotary drive control selector means of the type indicated in Figs. 1 and 1-A, push-button type control selector means may be used for controlling the operation of the drive mechanism. Fig. 1-B shows a conventional 50 type push-button mechanism which may be utilized for performing the control actions of a rotary selector of the type described in connection with Figs. 1 and 1-A. The selector mechanism of Fig. 1-B may be provided with

55 five push rods, only two of which are indicated at 85-4, 85-5, for performing the control actions performed by the selector contact blades 40-4 and 40-5 of Fig. 1. The push rods 85-4, 85-5 are slidably guided in guide slits or holes of spaced mounting bars 86 which are joined by two cross bars 87 into a substantially rigid frame work. Each push rod is biased by a biasing spring 88 to the normal released position in which rod 85-4 is shown. Furthermore, each 60 push rod is provided with a laterally projecting cam-like latch projection 89 and passes through a longitudinal slit 91 of a latch bar 90, slidably mounted in slits or holes of the cross bar 87 of the frame work so that when anyone of the 65 push rods is actuated from the released position to the operative position shown occupied by rod 85-5 the cam projection of the actuated push rod will laterally displace or shift the latch bar 90 to release all other push rods, such as 70 push rod 85-5 which is in the latch position,

75 push rod 85-5 which is in the latch position,

the latch bar 90 being returned by its biasing spring 83 to the latching position shown, thereby locking the operated push rod in the operated position.

A selector control mechanism of the type shown in Fig. 1-B may be provided with several sets of switches 95 one for each push rod and arranged so that when a push rod is actuated to the operated positions shown occupied by push rod 85-5, it will actuate its set of switches to the operative position. The sets of switches operated by the several push rods of Fig. 1-B may be utilized to perform the circuit control operations which are performed in Fig. 1 by selector switch blades 40-1 to 40-5.

The selector mechanism of the type shown in Fig. 1-B is also shown provided with additional switch contacts 83-1 suitably supported on the frame work so that the switch 83-1 is operated by the lateral movement of the push rod 90 each time one or the other of the push buttons 85-1 to 85-5 is actuated to the operative position. The additional switch 83-1 may be utilized for controlling the time action means such as relay 61-1 in the same manner as it is controlled by the switch contacts 83 of the control mechanism shown in Fig. 1-A for disabling the drive reversing mechanism during a predetermined timing interval, each time the drive control means is actuated from one operating condition to another operating condition. The mechanical motion of the individual push rods of a selector mechanism of the type shown in Fig. 1-B may be utilized for mechanically controlling the drive or the coupling mechanism of the type described above in connection with Fig. 1 in which case the lateral movement of the latch bar 90 may be utilized to move a lock element into locking engagement with the central portion of the coupling lever 4-35, preventing it from performing a drive reversing operation each time the selector means has been actuated from one operating condition to another, the lock element being interconnected with time action means which automatically return it to the coupling release position after a required time delay.

In Fig. 1-B each set of switches 95 is shown provided with releasable switch contacts 95-4 and 95-5 which are closed only for a short instance when the associated push rod is actuated and pushed inwardly to the operated position at the end of its inward stroke, the switch contacts 95-5 being released to the open position when the push rod is returned to the latch bar 90 at the level at which it holds the other switch contacts closed, in the manner shown in Fig. 1-B for the upper set of switches 95 of operated push rod 85-5. The releasable switch contacts 95-5 of the several sets of switches may be connected in parallel and used in lieu of the additional switch 83-1 for momentarily energizing the time action relay 61 each time one of the several push rods is operated to effect a drive control operation.

In Figs. 1-C to 1-E is shown a modified form of drive control arrangement of the general type described in connection with Fig. 1. It has a coupling mechanism similar to that of Fig. 1, a coupling lever 4-35 serves to establish forward-drive coupling connections in the full line position shown, and is movable therefrom to the dash-dot line position 4-35-R, in which it establishes a rewind drive coupling connections during the rewinding operation. The coupling lever 4-35 is biased by a toggle arm 4-43 either to the forward-drive full line position or to the

rewind drive dash-dot position 4-35-R in the manner described in connection with Fig. 1. However, instead of operating the coupling control lever 4-35 through by solenoids it is operated manually by means of a control lever 111 pivotally mounted on a fixed pivot 112, and movable between the full line position shown—to which it is brought for actuating the coupling mechanism to the forward-drive coupling position—and the dash-dot line position 111-A to which it is brought for actuating the coupling mechanism to the rewind-drive coupling position.

As indicated in Figs. 1-C and 1-D the control lever 111 is connected to a movable portion 15 of the coupling lever 4-35 by an energy storing connector element, shown in the form of a spring 114, so that when the control lever 111 is moved from the full line position to the dash-dot position 111-A, the biasing spring 114 will be charged and tensioned so that it exerts a force sufficient to bring the coupling lever 4-35 from the forward drive full line position shown to the dash-dot line rewind-drive position 4-35-R. The connector spring 114 is similarly effective in returning the coupling lever 4-35 from the dash-dot rewind-drive position 4-35-R to the forward drive full line position shown when the control lever 111 is returned from the dash-dot line position 111-R to the full line position 111.

Means are also provided for retaining or locking the coupling control lever 111 and preventing a reversal of the driving forces applied to the recording medium, before first bringing the recording medium to a stop, either in the full line position shown to which it is brought for establishing the forward drive conditions or the dash-dot line position 111-A to which it is brought for establishing the rewind-drive conditions. The locking means are shown in the form of two locking projections 113 held suitably affixed in the manner indicated in Fig. 1-E along the path of movement of the handle arm lever 111, so that it may be moved passed the interlocking projections 113. The portion of the control lever 111 is resiliently flexible so that it may be lifted from its position of locking engagement with a locking projection 113 and moved from one position to the other. The control arm of the control lever 111 being biased to establish locking engagement with a locking projection 113 when it is moved beyond it.

The drive control arrangement shown in Figs. 1-C and 1-E is also combined with time action means operative to prevent a reversal of the application of the driving forces to the recording medium before first stopping the recording medium. In the arrangement shown, there is provided to this end a blocking member 115 which is arranged to be moved into a position in which it blocks the movement of the coupling lever 4-35 from one coupling position to the other whenever the coupling control lever 111 is actuated from one control position to the other. The blocking element 114 is combined with time action means operative after the required time delay to retract blocking member 115 from the blocking position to a releasing position in which it permits the coupling lever 4-35 to perform a drive reversing operation under the control of the control lever 111.

In Figs. 1-C and 1-D the blocking member 115 is shown held by one arm of a rocking member 116 pivotally mounted on a fixed pivot 117, and carrying on its other arm a cam member 118, shaped so that when the control lever 111 is

moved from one control position to the other control position a portion thereof will engage the cam member 118 and actuate it to cause the rocker 116 to be rocked to a position in which its blocking member 115 blocks the movement of the coupling lever 4-35 from one position to the other.

As indicated in Figs. 1-C and 1-D, the rocker member 116 of the blocking mechanism is biased by a spring 119 to a releasing position in which the coupling lever 4-35 is free to be moved from one coupling position to the other. In addition, the rocker member has connected thereto time action means, shown in the form of a dash-pot 124, which permits the blocking member 117 being returned from the blocking position to the coupling release position only after a time delay sufficient to assure that the motor is first brought to a stop, whereupon the coupling mechanism is released to reverse the coupling connection under the action of the biasing connector 114 of the coupling control mechanism. The coupling-blocking rocker 116 is also utilized to open the motor energizing circuit each time the drive control mechanism is actuated to reverse the direction of the driving forces applied to the recording medium. In the arrangement shown, this is accomplished by providing a switch 126 connected in the circuit leading from the drive motor 4-20 of the recorder so that each time the drive reversal blocking mechanism is actuated to the blocking condition the motor circuit is opened, the switch 126 being re-closed only after the blocking mechanism such as shown in Figs. 1-C and 1-D has been returned to its coupling-releasing position shown.

Driving torque is transmitted to the reels through the drive ends of the reel drive shafts 4-12, 4-13 and the facing ends of the reel drive shafts 2-12, 2-13, respectively, of the reel holder unit 2-10 which are provided with coupling elements designed for automatically establishing detachable coupling interconnection between them when the reel holder unit 2-10 is coupled to the drive unit 4-10. In the arrangement shown, the two reel drive shafts 2-12, 2-13 of the reel holder unit are each provided with tapered splined coupling ends 2-14 arranged for automatic entry and sliding coupling engagement with internally splined female coupling collars 4-61 which form one end of coupling bellows 4-62, the other end of which is provided with a generally similar mounting collar 4-63 by means of which the coupling bellows 4-62 are affixed to the drive ends of the reel drive shafts 4-12, 4-13, respectively. The reels 33, 34 are fixed on the shafts 2-12, 2-13 which are journaled in a mounting plate 2-42 and in bearing members 2-44 in the detachable unit 2-10. The plate 2-42 is mounted on posts 2-41 provided on a base plate 2-11 of unit 2-10, the bearing members 2-44 being also mounted on the base plate. A cover 2-43 is provided for the detachable unit.

As indicated each of the reel drive shafts 2-12, 2-13 is provided with one-way brake means for subjecting it to braking forces tending to oppose the rotation of its reels during the unreeling operation. In the form shown, the braking means of each reel drive shaft 2-12, 2-13 is formed of two brake arms 2-60, each supported on relatively fixed pivots 2-61. The other ends of each of the arms 2-60 carry a brake shoe 2-62 which is held pressed against a cylindrical brake surface of a brake drum 2-21 by a biasing spring 75

2-83, one end of which is connected to the free end of one brake arm 2-60 and the other end of which is connected to the pivot pin 2-61 of the other brake arm. Specifically, the brake shoes 5 2-62, supported by brake arms 2-60, are carbon blocks diametrically disposed and equally spaced from the location of the reel axis. Since a substantially constant tension is to be maintained on the recording medium during a recording or playback process, the braking system employed in conjunction with each of the reels 33, 34 is operating while the recording medium is being drawn from that reel as supply reel. During such operation the braking action on the take-up reel is non-effective.

Two guide or aligning pins 4-65 projecting outwardly from and in front of the coupling wall 4-11 interfit with aligning holes or openings formed in the base wall 2-11 of the guide unit.

As indicated each of the reels 33, 34 is provided along one of its rims with a row of locking teeth 2-53 designed for cooperation with lock levers 2-54 pivotally mounted on suitable brackets extending from the base and subjected to the biasing action of biasing means shown in the form of springs 2-55. The biasing action of the spring urges the locking projection of the lock lever 2-54 to enter between the locking teeth 2-53 of the reel and lock it against rotation. The reel lock levers 2-54 are so positioned within the guide unit as to be automatically engaged by the aligning and guide pins 4-65 and actuated to the unlocking position shown whenever the guide unit is coupled in its aligned position to the drive unit 4-10.

Furthermore, the proper coupling engagement between the guide or reel holder unit 2-10 and the drive unit 4-10 is rendered simple and fool-proof by providing one of the coupling walls along which they are intercoupled, and more particularly the coupling wall 4-11 of the drive unit, with outwardly projecting boundary wall elements 4-67 forming a shelf-like nest or recess into which the guide unit 2-10 may be readily inserted as it is being brought into coupling interengagement with the drive unit. The height of the boundary walls is less than the height of the guide unit, or, in general, the boundary wall elements of the nest structure are so shaped as to make it possible to grip the guide unit 2-10 with the fingers when bringing it into the nest for coupling it to the drive unit or when removing it therefrom.

Latch switch 53 is operated by the handle 5-12 shown in an initial latching position. Angular movement of the handle 5-12 from the initial latching position to a locking position is effected by applying a forward thrust to the handle tip to release interlock finger 5-18, biased by means of a biasing spring 5-19. A counter-clockwise traverse of the interlock finger 5-18 through the interlock finger groove 5-20 is terminated and locked in the slot provided at the extreme end of the interlock finger groove. In the locking position pressure is transferred to the tension bar 5-17 through motion of a cam 5-13 within the slot 5-14 of the slide-plate 5-16. Through the eccentric motion of the cam within the slot, pressure is transmitted to the slide-plate 5-16. The handle 5-12 is pivotally supported to the cam 5-13 by the pin 5-15. The rounded ends of the tension bar 5-17 are passed through the bottom ends of the two latch arms 5-21 and 5-22 pivotally supported on pins 5-50, and 5-51. Motion of the tension bar

5-17 actuated by the associated elements of the handle mechanism effects the angular movement of the latch arms 5-21, and 5-22 about their pivot points 5-50, and 5-51 and effectively urge the latch hooks 5-52 and 5-53 to engage and grip latching studs located and anchored in the side walls of the guide or reel unit 2-10. Slots 2-33 and 2-34 of the guide unit 2-10 permit the entrance of and locking engagement of the latch hooks 5-52, and 5-53 to the latching studs.

As shown, each of the two latch hooks 5-52 and 5-53, projecting through the slots 2-35 and 2-36 of the forward coupling wall 4-11, are pivotally supported by pins 5-23 and 5-24 passing through the respective latch arms 5-21 and 5-22. A biasing spring 5-25 biases the latch hooks 5-52 and 5-53 angularly towards a latching position. Heel pieces 5-34 and 5-35 prevent movement beyond that position by the arresting springs 5-45, and 5-46.

The splined end of the reel shaft of the supply reel 33, is also utilized as a pinion which drives a gear 2-51 of a level wind shaft 2-52, the two ends of which are revolvably mounted in bearings seated in the base plate 2-11 of the guide unit and in its mounting bar 2-42 respectively. The level wind shaft 2-52 is provided with a cross thread, similar to that used in level wind mechanisms of fishing reels, the cross threads being engaged by a coupling pin located in a hub forming part of an arm carrying the transducer head 36, so as to impart to the transducer head a reciprocatory motion for level winding of the recording wire or filament 31 on one or the other of the reels 33, 34 on which it is reeled.

The two limit switches 51-F, 51-R are operated by the operating fingers 61-F, 61-R whenever the layers of the recording medium wound on the reel have reached their limit during the forward reeling or rewinding operation, respectively.

The guide unit 2-10 has also similarly mounted therein an additional warning switch 52-W arranged to be operated in a similar manner by operating finger 62-W. A short time before the operation of the limit switch 51-R, a warning is indicated, for instance by the lighting of a signal lamp, that the end of the recording medium is approaching and that the recording or playback process is about to be automatically stopped. Conventional micro-switches are used for the limit switches 51-F, 51-R and warning switch 52-W.

Other features of a practical form of magnetic recorder described above are more fully described in the publication of the Bureau of Ships, U. S. Navy, No. NAVSHIPS 365-1520, entitled "Recorder-Reproducer Equipment Model VRW-1, I. C. Instruction Book No. 130."

In Figs. 2 and 3 is shown another exemplification of the invention. A detachable guide unit 40 comprises a rectangular mounting plate 42 and a mounting bar 43 secured to the narrow ends of the mounting plate 42, so as to constitute therewith a self-supporting detachable unit on which are mounted the guide and impelling elements which serve to guide and impel a signal carrier, in the form of a long magnetic steel wire 45, past a magnetic signal transducing head 46 for magnetically recording or reproducing signals.

A cover 41, of sheet metal, which is detachably secured to the mounting bar 43, for instance, forms with the mounting plate 42 a casing which

houses all the elements of the guide unit 40. The magnetic wire carrier 45 is stored in spirally-coiled form on two like reels 49, 50 of non-magnetic material, such as aluminum. In the arrangement shown, each reel 49, 50 is formed of a cylindrical drum member 51 provided with flanges and suitably secured to a reel shaft so as to constitute a substantially rigid unitary structure journaled within the mounting plate 42 and the mounting bar 43.

The guide mechanism for such magnetic carrier transporting and storing arrangement is designed so as to assure that the complete guide and impelling mechanism is stopped for an instant whenever the direction of the motion of the signal carrier is changed and that in bringing the mechanism to a stop, the signal carrier is at all times maintained under tension.

In the arrangement shown in Fig. 2, brake means are shown in the form of an annular brake rim 58 of sheet metal, for instance, secured, as by welding, to the lower disc 54 of each reel 49, 50 and a brake band 61 faced with a suitable brake lining engaging the brake rim 58. The magnetic head 46 is impelled and guided in an up-and-down transverse movement by an endless cross-threaded leveling screw 72.

The carrier-guide reel holder unit 40, with its wire reels 49, 50 and other elements forming part thereof, is designed for detachable coupling in the proper operating position of a separate motor unit 41 so that all the carrier guide and impelling means are maintained in their proper operating conditions during the recording or reproducing operation, and also when the guide unit is removed from the motor unit, for storage, or the like.

As shown in Fig. 2, the motor unit 41 has an upwardly facing coupling wall 80 provided at its two side regions with aligning pins 181 interfitting with corresponding aligning holes formed in the facing portions of the mounting plate. The guide unit 40 is arranged to be automatically locked in the aligned coupled position on the motor unit 41 when placed on the mounting wall 80, for instance, by two spring arm latches 283 secured to the side walls of the motor unit 41, and having latch projections 84 overlying and interlockingly engaging the facing end edge portions of the mounting plate 42 within a cut-out provided in the end portions of the mounting bar 43 which are secured to the mounting plate.

The motor unit 41 is provided with two reel driving shafts 189, 190 suitably mounted therein so that when the reel holder 40 is placed in its aligned coupled position on the motor unit 41 the upwardly biased coupling members 89-1, 90-1 of the shafts automatically establish driving coupling connections with cooperating coupling surface elements 89-2, 90-2 formed on the lower ends of the two reel shafts.

The shaft 189, which serves to rotate the reel 49 when the wire 45 is wound thereon while recording or reproducing, is connected through a suitable speed reduction gearing connection 193 to an additional low-speed wire-leveling shaft 94 suitably supported within the motor unit so that when the reel holder 40 is placed in its operative coupled position on the motor unit 41, the upwardly biased coupling member 94-1 of the leveling shaft 94 automatically establishes a driving coupling connection with a cooperating coupling element 94-2 formed in the lower end of the leveling screw 72 so as to impart to the magnetic head 46 the proper up-and-down

transverse leveling motion, the rate of which is correlated to the rate at which the wire is wound on one or the other of the two reels 49, 50.

Automatic indicating mechanism is shown formed of a traveling nut pointer 101 guided longitudinally on two spindles 102, 103 mounted on supporting lugs 104 suitably secured to the mounting plate 42, spindle 102 being rotatable and being provided with a thread so that proper rotation thereof will cause the traveling-nut pointer 101 to move along a scale 106 for indicating thereon the progress of the recording or reproducing process, or, in general, of the winding operation.

Means are also provided for actuating the indicating mechanism spindle 102 at the proper rate of speed correlated to the rate at which the wire 45 is being moved from one reel to the other. One end of the threaded indicator spindle 102 is shown connected through a bevelled gear 107 to a bevelled gear 108 of a shaft 109, which is supported in bearings so that by rotating the shaft 109 at the proper rate, the indicator 101 will indicate on the scale 106 the relation of the length of the wire stored on the two reels. The proper rate of rotation may be imparted to the gear 108 and its shaft 109 through an additional indicator drive shaft 195 interconnected through a suitable reduction gear 96 with the reel drive shaft 189 and having an upwardly biased coupling element 195-1 arranged to automatically establish a coupling connection with a coupling end 195-2 formed on the lower end of the shaft section 109 through which the indicator spindle 102 is rotated.

It may also be of advantage to provide the carrier guide unit 40 with built-in corresponding reduction gearing mechanisms 93-1, 96-1 arranged so that the rotation of the reel 49 imparts the required rate of rotation to the level winding screw 72 and to the indicator spindle 102.

The driving arrangement and the associated control arrangement are designed and correlated that when the direction of the motion of the signal carrier is reversed, the selective application of the driving forces and the braking forces to the two reels is performed in a predetermined timed sequence to assure that the two reels and the carrier stored thereon are first brought to a positive stop by the action of the braking forces as the driving force is removed from one reel and applied to the other.

The driving force may be applied to the two reels either by a single motor, such as an electric motor, or two separate motors. In either case, the application of the driving force to each reel is interlocked with the application of a braking force thereto so that whenever the driving force is removed, a sufficient braking force is applied to assure that the reel with the mass of the coiled signal carrier carried thereon is brought to a stop in the required short interval before the driving force is applied to the other reel.

The interlocked application of the driving and braking forces to each reel may be controlled by electrically operated or by mechanically operated elements or by a combination of electrically and mechanically operated elements. In accordance with the invention, the elements governing the controlled interlocked application of the driving and braking forces to each reel are so designed that even in case the electric power, used for providing the mechanical driving forces and the electrical control actions, fails, the two reels with the wire stored thereon will at all times be sub-

jected to sufficient braking forces as to assure that they are brought to and remain stopped and that the signal carrier wound thereon remains under tension.

Fig. 2 illustrates diagrammatically one form of drive arrangement based on the foregoing principles which uses only one electric motor 120. This motor 120 as well as the other electrically actuated elements referred to herein may be either of the conventional A. C. or D. C. type, but in order to simplify the description, they are indicated as being supplied from an electric source designated by (+) and (-) signs.

In the arrangement shown in Fig. 2, the motor 120 is shown driving through a speed reduction gearing, including gears 121, 122, and 122-1, a driving gear 123 revolvably mounted on reel shaft 189 for applying counterclockwise rotational driving forces to reel 49 for winding thereon the wire during recording or reproducing. The motor is further connected through a gear 224 to a gear 125 revolvably mounted on the shaft 190 for applying a clockwise rotational force to reel 50 for rewinding thereon the wire at a higher speed after a recording or reproducing operation, the reel 50 being driven, for instance, at twice the speed reel 49 is driven.

Each of the two reel shafts 189, 190 is provided with means for selectively applying thereto the required rotational driving and the braking force. The gear discs 123, 125 which revolve freely on the two reel shafts are shown fixed against displacement along their shafts. Each of the two reel shafts is also shown provided with a coupling unit 226, 127, respectively, for selectively coupling each shaft either to the associated driving gear 123, 125 or to an associated brake member 128.

Each shaft 189, 190 is shown connected to its coupling member 226, 127 by a key pin 131 extending through the shaft and through a slit 132 of the sleeve-like coupling-member portion slidably mounted on the shaft so as to permit limited slidable movement of the coupling member 45 along the shaft while being fixed thereon against rotation.

Each coupling member 226, 127 has a coupling surface rim 133 provided with a coupling lining movable into coupling engagement with the facing coupling surface of the corresponding driving gear 123, 125 so as to selectively apply their driving forces to the respective reel shafts 189, 190. Each coupling member also has a braking rim 134 provided with a suitable brake lining surface movable in opposite direction into braking engagement with the facing braking surface of a stationary brake member 128 so as to selectively apply a braking force sufficient to promptly stop the rotation of the respective reel shafts.

Each coupling member 226, 127 is shown linked to a pivotally mounted coupling lever 135, which is biased by a spring 137 so as to cause the associated coupling member to be maintained in the braking position. Each coupling member is also shown provided with cam follower projections 141, the ends of which are shown riding across a ball 142 on a cam surface of a control member 143 mounted for sliding motion from the left-hand position, indicated in Fig. 2, in which the raised portion of its cam surface region 144 presses the coupling surface 133 of the coupling member into coupling engagement with the driving gear 123 for driving reel shaft 189, to the analogous right-hand position, in which the other 75 cam surface region correspondingly raises the

other coupling member 127 from its released lower position in which its brake rim 134 is pressed into braking engagement with the associated brake member 128. A suitable resilient element of the required stiffness will be embodied in the connection between the shafts 189, 190 and their respective coupling members, for instance, in the form of a spring interposed between the lower end of each shaft, and the bottom surface of the sleeved brake-member portion.

As shown, a longitudinal sliding motion imparted to the cam-like control member 143 from its position shown toward a corresponding position to the right in a predetermined timed sequence of operations, automatically effects a reversal of the coupling and braking connections of the two reel shafts, the operation of the cam region 144 causing the coupling member 226 to be first returned to the lower positions in which shaft 89 opens its coupling connection to gear 123 and establishes its braking connection with its brake member 128, followed by the operation of the other cam region which raises the other coupling member 127 to its upper position in which shaft 190 opens its braking connection to its braking member 128 and establishes its driving connection to its driving gear 125.

The control member 143 may be actuated to its different operating positions, either manually or by automatic means locally or remotely controlled. Fig. 2 indicates the principles of one form of the automatic control arrangement. The control 143 has rotatably mounted on a face thereof a cam 146 which is arranged to be continuously rotated, for instance, by a small motor 147-1 through a suitable gearing. As also indicated in Fig. 3, two catch pins 151, 152 are arranged for sliding motion in a direction transverse to the face of the control member 143 so that when either one or the other of the pins 151, 152 projects beyond the face of the control member 143, it is engaged by the periphery of the rotating cam 146 and pushed thereby to bring the control member 143 to one of its end positions in which one or the other of the coupling members 226, 127 is selectively actuated to the raised position while the other is lowered. The two catch pins 151, 152 may be arranged to be normally biased to an inward position in which their ends are out of the path of the rotating cam 146 and one or the other of the actuating pins 151, 152 is arranged to be selectively pushed outwardly into engagement with the cam disc by selective actuation of an associated magnet coil 151-1, 152-1.

The required control motion may be imparted to the control member 143 either by a separate small auxiliary motor 147-1 or, if the driving motor is maintained continuously energized and the application of the driving force is controlled solely by the operation of a coupling member, such as the coupling members 226, 127, the main driving motor 120 may be directly utilized for supplying power through a suitable reduction gearing to an element, such as the cam 146 which is utilized for moving the control member to its different operating positions.

The two magnets 151-1, 152-2 are shown controlled electrically through either one of the actuating switches 153, 154 of a circuit from a source indicated by (+) and (-) signs. The circuit to each magnet also includes interlocking switches 155, 156, respectively, which are biased to a closed position and are actuated to an open position by one of the two nose projections 157 pro-

vided in the two regions of the control member 143 so that when either one of the actuating switches 153, 154, for instance, switch 154, is closed, it will energize magnet 152-1 to actuate pin 152 to the outward position, causing the cam to shift the control member to the right in which end position, the right-hand nose projection 157 will open the circuit to the magnet 152-1 and restore its catch pin 152 to the retracted position.

10 The interlocking arrangement assures that the control member 143 always remains in one of the end positions and that the two actuating pins 151, 152 remain in their retracted inoperative positions and that they are actuated to their operative positions only upon actuation of the associated operating switches 153, 154. Furthermore, the catch pins 151, 152 are retracted to their inoperative position through the opening of their associated interlocking switch 155, irrespective of whether their respective actuating switches 153, 154 are closed or not.

15 The closure of either one or the other of the two switches 153, 154 results in automatic reversal of the connection between the driving force and one or the other of the reel shafts 189, 190 in their proper sequence so that the coupling connection from the driving force to the reel shaft which was being driven, is first broken and a driving connection is established to the shaft of the other reel and the braking action removed therefrom.

20 Obviously, a single movable blade switch may be substituted for the two actuating switches 153, 35 154. As indicated in the drawing, the two switches may be also arranged for remote operation through suitable relay coil arrangements 158, 159 indicated diagrammatically as leading to a central amplifier and control unit 160 which 30 combines all the amplifier and control circuits associated with the device for controlling the recording, reproducing, rewinding and other operations, the control device being shown provided with a suitable number of actuating buttons 161 40 arranged so that pushing a button starts and 45 brings about the automatic performance of the desired operation.

25 The elements of the cam surface regions of the control member 143 are made sufficiently long, and the range and the speed of the motion imparted to the control member 143 either manually or automatically, for instance, by the operation of the cam 146, is so chosen that when 50 effecting a reversal of the driving connections, for instance, from the conditions shown in Fig. 2 in which reel 49 is driven in clockwise direction, to the condition in which reel 50 is driven in counterclockwise direction, the driving connection of reel 49 to the source of its driving force, is first opened and a brake action is applied thereto so that reel 49 is positively stopped, for an instant before the further motion of the control member 143 to the opposite position 55 opens the braking connection of reel 50 and establishes its driving connection to the source of its driving force, represented by gear 125.

60 In order to make it possible to drive the reels with a relatively small motor, the drive-brake-force applying members 226, 127 may be arranged 65 for electrical actuation only, as by magnets indicated at 139, so that whenever a driving force is applied to a reel, the braking action applied thereto is automatically removed, and that removal of the driving force automatically restores 70 the braking action applied to the respective reels,

and that in reversing the drive connections, the series of operations involved in stopping the reels before applying the reverse driving forces is automatically performed in the proper timed sequence, as by an arrangement of time-action relays operating in an automatically interlocked timing sequence.

As indicated in Fig. 2, the interlocking switches 162, 163, through which the selective application of the braking and driving forces is determined, may be controlled by the operation of the control member 143 which, as shown, has two additional nose projections 164, 165 which selectively close the circuit to the driving motor 120 only when the control magnet 139 of the associated coupling member 226, 127 is actuated to remove the braking action and to permit the application of the motor driving force to the associated reel 49, 50, respectively, as well as to assure the required time sequence of operations involved in reversing the drive connections as explained above, with or without the combined use of the control member 143 itself for directly performing the drive and brake-coupling or uncoupling operations.

Means are also provided for automatically interlocking the operation of the elements of the motor unit 41 with the operation of the elements forming part of the reel holder unit 40 as by means of a pair of multi-pole electric connector members 171, 172, such as plug and socket members of the type used for interconnecting amplifier circuit devices, mounted in outwardly exposed positions on the mounting wall 42 of the guide unit 40 and on the coupling wall 80 of the motor unit 41. The terminal elements of the coupling member 171 are shown connected through leads to the magnetic head, and the terminal elements of the coupling member 172 are shown connected through a cable 173 to the amplifier and control unit 160, only portions of the cable 173 being shown for the sake of simplicity. The connector elements 171, 172 as well as all other coupling elements, mechanical or electrical, which serve to interconnect operating parts of the reel holder 40 and the motor unit 41, are of the self-centering type and are designed to embody sufficient self-restoring yieldability, as to assure that when the reel-holder guide unit 40 is coupled to the motor unit 41 in its automatically aligned position determined by the register pins 61, all the coupling connections are properly established.

Fig. 2 also shows automatic interlocking means for stopping the driving mechanism when a predetermined part, for instance, all but the anchoring end, of the signal carrier has been transported from one reel to the other. The traveling indicator nut 101 is designed to engage and push to one or the other side the stop blocks 174, for instance, adjustably affixed to guide rod 103 so as to actuate the guide rod 103 to the right or the left and cause its end portions 103-1 thereof to open one or the other of two interlocking switches 175 mounted in the motor unit 41 and having portions projecting, for instance, into the path of motion of the ends 103-1 of the guide rod 103.

The interlocking switches 175 are utilized to perform an operation which results in automatically stopping the motion of the reels whenever one of the two switches 175 is actuated from its non-actuated position shown. These switches may be utilized either to control the operation of the driving motor 120 or of any other elements associated with the transmission of the driving

forces and the application of the braking forces to the two reels.

In the arrangement shown, the interlocking switches 175 are connected in the circuit through which the motor 120 is energized, the motor circuit being completed through its interconnection by way of either lead 176 through a suitable control device of the amplifier unit to a power supply terminal 177, or through a similar connection of the other lead 178 to a similar power supply lead 177.

There are also provided means for automatically interlocking the operation of the driving mechanism with the parts which control the timing of the coupling and braking actions. As shown in Fig. 2, an additional switch element 182, 183 may be combined with two switch elements 162, 163 so as to be automatically actuated therewith by the nose projections 164, 165, respectively, of the control member 141, when the latter reaches or leaves one of its end positions, respectively, the additional switches 182, 183 are shown interconnected in the two energizing circuits 176, 178, respectively, of the driving motor 120.

This interlocking arrangement assures that the electrical motor drive and control connections can be established only in the end position of the mechanical time-action control element 143, after all mechanical coupling and uncoupling operations have been performed in their proper timed sequence, and that even in case the electric power, required for energizing the driving motor 120 and the various electric control circuits, fails, the reels will remain in their arrested position and the signal carrier wire 45 will be kept under tension.

As used herein in the specification and claims the expression "magnetic record transducing" is intended to mean either the operation of magnetically recording signals on a magnetic recording medium, or the operation of reproducing magnetically recorded signals, or the operation of erasing magnetically recorded signals, or any combination of two or more of these operations.

It will be apparent to those skilled in the art that the novel principles of the invention disclosed herein in connection with specific exemplifications thereof will suggest various other modifications and applications of the same. It is accordingly desired that in construing the breadth of the appended claims they shall not be limited to the specific exemplifications of the invention described above.

I claim:

1. In a magnetic record transducing apparatus for transducing magnetic records, such as recording or reproducing magnetic signals: a long magnetic record track; magnetic signal transducing means including windings for transducing records by varying magnetic flux interlinking said windings and a moving element of said track; guiding means for guiding and impelling said track past said transducing means including two rotatably mounted reels storing the major part of said track in coiled form so that a driving force imparted to one reel for winding thereon said track will cause the track to rotate the other of said reels while the track is being withdrawn therefrom; drive means actuatable to apply driving forces to one of said reels for winding thereon the record track and braking means for applying braking forces tending to stop the rotation of said reels; and control means for selectively controlling the application of said driving forces of said driving means to either one of said reels;

said control means including time-action means and being so designed that when it is actuated to remove the driving forces from one reel and to apply the driving forces to the other reel said control means first removes said driving forces from said one reel and cause said one reel to be substantially stopped by the action of said braking forces, and that after a time delay determined by said time action means said control means cause said driving forces to be applied to said other reel after said one reel has been first substantially stopped.

2. In a magnetic record transducing apparatus for transducing magnetic records, such as recording or reproducing magnetic signals: a long magnetic record track; magnetic signal transducing means including windings for transducing records by varying magnetic flux interlinking said windings and a moving element of said track; guiding means for guiding and impelling said track past said transducing means including two rotatably mounted reels storing the major part of said track in spirally-coiled form so that a driving force imparted to one reel for winding thereon said track will cause the track to rotate the other of said reels while the track is being withdrawn therefrom; drive means actuatable to apply driving forces to one of said reels for winding thereon the record track and braking means for applying braking forces tending to stop the rotation of said reels: said drive means including electrically energized motor means and coupling means actuatable to establish or remove a driving connection from said motor means to either of said reels; and control means for selectively controlling the application of said driving forces of said driving means to either one of said reels; said control means including time-action means and being so designed that when actuated to remove the driving forces from one reel and to apply the driving forces to the other reel said control means operate in a predetermined sequence under the control of said time-action means to first de-energize said motor means and cause said reels to be substantially stopped by the action of said braking means, then remove the driving connection from said one reel, and thereafter apply the driving forces to said other reel after said one reel has been first substantially stopped.

3. In a magnetic record transducing apparatus for transducing magnetic records, such as recording or reproducing magnetic signals: a long magnetic record track; magnetic signal transducing means including windings for transducing records by varying magnetic flux interlinking said windings and a moving element of said track; guiding means for guiding and impelling said track past said transducing means including two rotatably mounted reels storing the major part of said track in coiled form so that a driving force imparted to one reel for winding thereon said track will cause the track to rotate the other of said reels while the track is being withdrawn therefrom; drive means actuatable to apply driving forces to one of said reels for winding thereon the record track and braking means for applying braking forces tending to stop the rotation of said reels; and control means for selectively controlling the application of said driving forces of said driving means to either one of said reels; said control means including preventive means and being so designed that when actuated to remove the driving forces from one reel and to apply the driving forces to the other

reel said control means operate in a predetermined sequence under the control of said preventive means to first remove the driving forces from said one reel and cause said reels to be substantially stopped by the action of said braking means, and after a predetermined time delay to apply the driving forces to said other reel after said first reel has been first substantially stopped.

4. In a magnetic record transducing apparatus for transducing magnetic records, such as recording or reproducing magnetic signals: a long magnetic record track; magnetic signal transducing means including windings for transducing records by varying magnetic flux interlinking said windings and a moving element of said track; guiding means for guiding and impelling said track past said transducing means including two rotatably mounted reels storing the major part of said track in coiled form so that a driving force imparted to one reel for winding thereon said track will cause the track to rotate the other of said reels; drive means actuatable to apply driving forces to one of said reels for winding thereon the record track and braking means for applying braking forces tending to stop the rotation of said reels; said drive means including electrically energized motor means and coupling means actuatable to establish or remove a driving connection from said motor means to either of said reels; and control means for selectively controlling the application of said driving forces of said driving means to either one of said reels; said control means including time-action means and being so designed that when actuated to remove the driving forces from one reel and to apply the driving forces to the other reel said control means operate in a predetermined sequence under the control of said time-action means to first de-energize said motor means to cause said reels to be substantially stopped by the action of said braking means, then uncouple said motor means from said one reel, and after a predetermined time delay apply the driving forces to said other reel after said first reel has been first substantially stopped.

5. In a magnetic record transducing apparatus for transducing magnetic records, such as recording or reproducing magnetic signals: a long magnetic record track; magnetic signal transducing means including windings for transducing records by varying magnetic flux interlinking said windings and a moving element of said track; guiding means for guiding and impelling said track past said transducing means including two rotatably mounted reels storing the major part of said track in coiled form so that a driving force imparted to one reel for winding thereon said track will cause the track to rotate the other of said reels; drive means actuatable to apply driving forces to one of said reels for winding thereon the record track and braking means for applying braking forces tending to stop the rotation of said reels; said drive means including electrically energized motor means and coupling means actuatable to establish or remove a driving connection from said motor means to either of said reels; and control means for selectively controlling the application of said driving forces of said driving means to either one of said reels; said control means including time-action means and being so designed that when actuated to remove the driving forces from one reel and to apply the driving forces to the other reel said control means operate in a predetermined sequence under the control of said time-action means to first de-

energize said motor means to cause said reels to be substantially stopped by the action of said braking means, then uncouple said motor means from said one reel, thereafter couple said motor means to said other reel, and then energize said motor means after said one reel has been substantially stopped.

6. In a magnetic record transducing apparatus for transducing magnetic records, such as recording or reproducing magnetic signals: a long magnetic record track; magnetic signal transducing means including windings for transducing records by varying magnetic flux interlinking said windings and a moving element of said track; guiding means for guiding and impelling said track past said transducing means including two rotatably mounted reels storing the major part of said track in spirally-coiled form so that a driving force imparted to one reel for winding thereon said track will cause the track to rotate the other of said reels; drive means including electric motor means actuatable to selectively apply driving forces to one of said reels for winding thereon the record track and braking means for applying braking forces tending to stop the rotation of said reels; and control means for selectively controlling the application of said driving forces of said driving means to either one of said reels; said control means including time-action means and being so designed that when it is actuated to remove the driving forces from one reel and apply the driving forces to the other reel said control means first de-energize said motor means and remove said driving forces from said one reel and cause said one reel to be substantially stopped by the action of said braking forces and that after a time delay determined by said time action means said control means cause said driving forces to be applied to said other reel and energizes said motor after said one reel has been first substantially stopped.

7. In a magnetic record transducing apparatus for transducing magnetic records, such as recording or reproducing magnetic signals: a long magnetic record track; magnetic signal transducing means including windings for transducing records by varying magnetic flux interlinking said windings and a moving element of said track; guiding means for guiding and impelling said track past said transducing means including two rotatably mounted reels storing the major part of said track in spirally-coiled form so that a driving force imparted to one reel for winding thereon said track will cause the track to rotate the other of said reels; drive means including electric motor means and coupling means actuatable to selectively couple said motor means to one of said reels for winding thereon the record track and braking means for applying braking forces tending to stop the rotation of said reels; and control means for selectively controlling the application of said driving forces of said driving means to either one of said reels; said control means including time-action means and being so designed that when it is actuated to remove the driving forces from one reel and apply the driving forces to the other reel said control means first de-energize said motor means and uncouple said motor means from said one reel and cause said one reel to be substantially stopped by the action of said braking forces and that after a time delay determined by said time action means said control means couple said motor means to said other reel and energizes said motor after said one reel has been first substantially stopped.

8. In a magnetic record transducing apparatus for transducing magnetic records, such as recording or reproducing magnetic signals: a long magnetic record track; magnetic signal transducing means including windings for transducing records by varying magnetic flux interlinking said windings and a moving element of said track; guiding means for guiding and impelling said track past said transducing means including two rotatably mounted reels storing the major part of said track in spirally-coiled form so that a driving force imparted to one reel for winding thereon said track will cause the track to rotate the other of said reels; drive means actuatable to apply driving forces to one of said reels for winding thereon the record track and braking means for applying braking forces to the reel from which the record track is unreeled; and control means for selectively controlling the application of said driving forces of said driving means to either one of said reels; said control means being so designed that when it is actuated to remove the driving forces from one reel and apply the driving forces to the other reel said control means first removes said driving forces from said one reel and causes said one reel to be substantially stopped by the action of said braking forces exerted on the other reel and that after a time delay determined by said time action means causes said driving forces to be applied to said other reel after said one reel has been first substantially stopped.

9. In a magnetic record transducing apparatus for transducing magnetic records, such as recording or reproducing magnetic signals: a long magnetic record track; magnetic signal transducing means including windings for transducing records by varying magnetic flux interlinking said windings and a moving element of said track; guiding means for guiding and impelling said track past said transducing means including two rotatably mounted reels storing the major part of said track in spirally-coiled form so that a driving force imparted to one reel for winding thereon said track will cause the track to rotate the other of said reels; drive means actuatable to apply driving forces to one of said reels for winding thereon the record track and braking means for applying braking forces tending to stop the rotation of said reels; said drive means including electrically energized motor means and coupling means actuatable to establish or remove a driving connection from said motor means to either of said reels; and control means for selectively controlling the application of said driving forces of said driving means to either one of said reels; said control means including time action means and being so designed that when actuated to remove the driving forces from one reel and apply the driving forces to the other reel said control means operates in a predetermined sequence under the control of said time action means to first de-energize said motor means and cause said reels to be substantially stopped by the action of said braking means, exerted on the other reel; thereafter remove the driving connection from said one reel, and thereafter apply the driving forces to said other reel after the first reel has been first substantially stopped.

10. In a magnetic record transducing apparatus for transducing magnetic records, such as recording or reproducing magnetic signals: a long magnetic record track; magnetic signal transducing means including windings for transducing records by varying magnetic flux inter-

linking said windings and a moving element of said track; guiding means for guiding and impelling said track past said transducing means including two rotatably mounted reels storing the major part of said track in spirally-coiled form so that a driving force imparted to one reel for winding thereon said track will cause the track to rotate the other of said reels; drive means actuatable to apply driving forces to one of said reels for winding thereon the record track and braking means for applying braking forces tending to stop the rotation of said reels; said drive means including electrically energized motor means and coupling means actuatable to establish or remove a driving connection from said motor means to either of said reels and control means for selectively controlling the application of said driving forces of said driving means to either one of said reels; said control means including time action means and being so designed that when actuated to remove the driving forces from one reel and apply the driving forces to the other reel said control means operates in a predetermined sequence under the control of said time action means to first de-energize said motor means and cause said reels to be substantially stopped by the action of said braking means, exerted on the other reel; thereafter uncouple the motor means from said one reel, then couple the motor means to said other reel, and thereafter energize said motor means so that the driving forces are applied to said other reel after said first reel has been first substantially stopped.

11. In a magnetic recording apparatus: a long magnetic record track; magnetic signal transducing means for recording and reproducing signals by magnetic flux variations interlinking said transducing means and an element of said track moving past it; guiding means for guiding and impelling said track past said transducing means including two revolvably mounted reels for storing the major part of said track in spirally-coiled form so that a driving force imparted to one reel for rotating it and winding thereon said track will cause the track to rotationally drive the other of said reels while being withdrawn therefrom; drive means actuatable to selectively apply driving forces to one of said reels for rotating the same and brake means for applying braking forces to said one reel for stopping rotation of said reels; and control means for controlling the operation of said drive means and said brake means operative to remove the braking forces from said one reel when the driving forces are applied thereto and to apply braking forces when the driving forces are removed therefrom; said control means being arranged to prevent the application of the driving forces to one reel when

driving forces are applied to the other reel; said control means including time action means and being so designed that upon actuation thereof to remove the driving forces from one reel and apply driving forces to the other reel said control means operate in a predetermined sequence under the control of said time action means to first remove the driving forces from said one reel and cause said one reel to be substantially stopped by the action of said braking forces before the driving forces are applied to the other reel.

12. A magnetic recording apparatus as defined in claim 11, in which the control means include interlocking means operative upon actuation of the control means to remove the driving forces from one reel and apply driving forces to the other reel to first cause the application of braking forces to said one reel and prevent the application of driving forces to said other reel before said one reel is stopped.

13. A magnetic recording apparatus as defined by claim 11, in which the control means include interlocking means having a movable time-action member operative upon actuation of the control means to remove the driving forces from one reel and apply driving forces to the other reel to first cause the application of braking forces to said one reel and prevent the application of the driving forces to said other reel before said one reel is stopped.

14. A magnetic recording apparatus as defined by claim 11, in which the control means including interlocking means operative upon actuation of the control means to remove the driving forces from one reel and apply driving forces to the other reel to first cause the application of braking forces to said one reel and prevent the application of driving forces to said other reel before said one reel is stopped.
